CLOSURE FOR CONTAINERFrederick C. Morrow, 638 S. Michigan St., Plymouth, Ind.
Filed Dec. 1, 1961, Ser. No. 156,391
5 Claims. (Cl. 229—7)

The present invention relates to a closure for a container and more particularly to a closure for a box, carton and the like.

Powdered and granular materials for household use are extensively sold in dispenser type cartons or boxes having some form of pour spout or lip in combination with a door or lid hinged to the carton or box at the side, top or bottom of the pour opening. One type extensively used consists of a trough-like metal chute hinged to the edge of the box or carton at the bottom of a generally rectangular opening. While the position of the opening is most convenient for holding the carton and pouring the contents therefrom, the metal chute-like closure is difficult to open initially, often resulting in a ragged edge around the opening and/or displacement of the closure so that it does not effectively thereafter close the opening. Further, in order to open the closure, it is necessary to place a thin instrument, usually a finger or thumb nail beneath the closure and pry outwardly. This is not only hazardous but is unsanitary and may result in serious contamination of any food products poured from the carton and injury to the user. It is therefore one of the principal objects of the invention to provide a closure for a carton or box of the aforementioned type having an opening, which can easily be removed from the opening and replaced therein without the use of any implement or finger nails, and which when open provides a well defined, readily used and convenient pour opening.

Another object of the invention is to provide a closure for a pour opening in containers of the aforesaid type which is attached to the container and is substantially flush with the external surface thereof when closed and which can be removed completely from the opening without detaching it from the container.

Still another object of the invention is to provide a closure for containers of the foregoing type, which will remain open while the contents are being poured from the container without being held open, yet which will automatically close and seat itself when initially nudged toward closed position and which will remain closed until intentionally opened again by the user.

A further object is to provide a container-closure combination having an original seal for preventing the container from being opened without tell-tale evidence that the container has been tampered with, and for preventing accidental displacement of the closure during shipping and handling before sale, and which positively and effectively seats itself when closed to prevent leakage of the container contents around the closure as long as it remains closed, and will not open unaided when the container is inverted.

Additional objects and advantages of the invention will become apparent from the following description and accompanying drawings, wherein:

FIGURE 1 is a perspective view of a container such as that used for home detergents, showing the closure removed for opening thereof;

FIGURE 2 is a top plan view of the container shown in FIGURE 1, showing in broken lines the closure in closed position;

FIGURE 3 is a fragmentary elevational view of the edge of the container shown in FIGURES 1 and 2, showing the closure in sealed position, illustrating the manner in which the container is sealed for shipment;

FIGURE 4 is a fragmentary vertical cross sectional

2

view of the container shown in the preceding figures, showing the closure in its closed position, the section being taken on line 4—4 of FIGURE 2;

FIGURE 5 is a fragmentary horizontal cross sectional view of the closure, taken on line 5—5 of FIGURE 3, showing the closure in its open position;

FIGURE 6 is a plan view of a completed blank from which the container shown in the preceding figures is made; and

FIGURE 7 is an edge elevational view of the container blank shown in FIGURE 6.

Referring more specifically to the drawings, the container 10 shown in FIGURE 1 is a carton or box of generally conventional construction, produced from stiff paper, cardboard or the like, consisting of sides 12 and 14 and ends 16 and 18 and top and bottom 20 and 22, respectively, secured together at their edges to form a completely enclosed container having the present combination opening and closure therefor indicated generally by numeral 24.

With the exception of the combination opening and closure therefor, the box structure just described may be considered conventional for the purpose of the present description, and may be of various sizes and shapes, although the type shown is used extensively for the sale of powdered and granular food preparations and detergents and the like. Referring to FIGURE 6, which illustrates the manner in which the present container is produced from a single sheet of stiff paper or cardboard, the two sides 12 and 14 and ends 16 and 18 are joined together and folded therebetween along lines 26, 28 and 30 to form a rectangular enclosure. Flap 32 is folded along line 34 and is joined to the opposite edge of side 12 along the internal surface thereof, to secure the rectangular configuration formed by the two sides and ends together. Thereafter tabs 36 and 38 are folded downwardly and inwardly, followed by panels 40 and 42, the latter constituting the upper and outer surface of the box. Flaps 44 and 46 are folded inwardly and upwardly, followed by panels 48 and 50, the latter forming the lower external surface of the box. The flaps and panels are secured together by any suitable, hard-drying adhesive material which will securely hold the parts thereof together and the entire box in a rectangular, enclosed structure. In order to strengthen the joints between the top and bottom panels and the edge panels 16 and 18, flaps 52 and 54 at the upper end and flaps 56 and 58 at the lower end extend upwardly over the edge panels 16 and 18 and are secured thereto, producing a leak-proof joint between the top panels and the edges. Flap 52 serves an additional purpose which will be more fully explained herein-after.

The pour opening 60 for the container is provided in the upper end of edge 18, and in the preferred embodiment is round or substantially round as shown in the drawings. It may be of various sizes, but preferably is sufficiently small that a strengthening structure is provided on all sides of the opening in edge 18. Surrounding opening 60 is a recessed ledge 62 which forms a seat for the closure, and is preferably formed by an insert 64 secured to the internal surface of edge 18, the insert being secured in place on the blank as shown in FIGURE 6 and secured thereto by any suitable adhesive material.

65 The closure 70 seats in opening 60 and cooperates with ledge 62 to form an effective seal for the container. This closure consists of a dome-shaped body portion 72 and an annular flange 74 around the body portion and joined integrally thereto, the flange being adapted to seat on annular ledge 62. The largest diameter of body 72, i.e. the portion 76 adjacent flange 74, is

substantially the same size, preferably slightly smaller than opening 60, so that it will pass inwardly readily and into the hole and permit flange 74 to seat effectively on ledge 62. The diameter of outer hole 78, defining ledge 62, is preferably only slightly larger than the external diameter of flange 74 so that a relatively smooth surface will be provided between the exterior surface of end panel 18 and the external surface of flange 74, and an additional retaining means is provided between the flange and the edge of the opening to prevent accidental dislodgement of closure 70. In order to assist in removing the closure from hole 60, a small handle or tab 89 is provided across the recessed portion 82 of the closure, the recessed portion following the contour of the domed body 72.

In order to seat and retain the closure in hole 60, a resilient means, such as a rubber member 84, is secured at one end to the closure by a fixture 86 and at the other end to the upper panel 40 of the box. The means of securing the end of resilient member 84 to the box may be a number of different structures, the one shown consisting of a hole 88 through panel 42, through which the end of member 84 extends and a pin 90 on the upper side of panel 42 above hole 88, the resilient member 84 shown as a rubber band looped around fixture 86 and around pin 90. Any suitable stretchable material may be used, including a small coiled metal or plastic spring, or the like, which permits the closure to be lifted from opening 60 and placed to one side as illustrated in FIGURES 1 and 5. In the form shown in the drawings, it is preferable to secure the resilient member to the box in the manner illustrated at the time the box is assembled; however, various other types of securing means, including merely a tab on the internal surface of one of the panels, may be used, and the resilient member can be secured thereto after the box has been fully assembled and, if desired, filled, before the closure securing means is attached thereto. In the embodiment shown, pin 90 is positioned over hole 88 between panels 40 and 42. In securing the pin and resilient member in place, the container may be assembled with panel 42 secured in place and panel 40 in raised position. A special tool extending through opening 60 projects the inner end of the resilient member through hole 88 for securing with pin 90.

As illustrated in FIGURE 3, tab 52 is preferably secured by a suitable adhesive to the external edge panel 18 with the lower edge thereof extending downwardly over a portion of closure 70, thus providing an additional sealing or securing means for closure 70 while the box is being shipped and stored on the shelf. When it is desired to open the box, the finger can be placed in recess 82 beneath tab 52 and the tab lifted, breaking the seal provided thereby. The closure may then be easily lifted from hole 60 to open the container. The sealing of closure 70 by tab 52 provides tell-tale evidence if the container has been tampered with before it is received and opened by the ultimate user.

In the use of the present container closure combination, the user opens the container by lifting tab 52, breaking the seal provided thereby, and grasping handle or tab 89 and lifting the closure from hole 60, thus substantially fully exposing the hole for the discharge of the contents in the container. The closure, when lifted from opening 60, is placed at the side as illustrated in FIGURES 1 and 5 where it is held firmly by the resilient member 84 urging the closure inwardly and the periphery of flange 74 against the periphery of hole 60, thereby retaining the closure in a fixed position while the contents of the container are being poured therefrom. The closure will snap back into its fully closed position by merely nudging it toward the opening, thereby permitting resilient member 84 to pull the closure inwardly into the hole and seat flange 74 firmly on ledge 62. The closure

will remain in this position until it is intentionally removed by the user.

While only one modification of the invention has been described in detail herein, various changes and modifications may be made to suit requirements.

I claim:

1. In a container having an opening in an upper portion thereof: a panel mounted on the inner side of said portion and having a round hole therein smaller than said opening and in conjunction with said portion forming a recess around said hole, a closure of plastic material having an inwardly protruding, dome-shaped body with a hemispherical recess on its external side, a handle extending across said body recess, a laterally extending annular flange joined integrally to and disposed around the edge of said body for seating on said panel in said first mentioned recess and around said hole, a fixture secured to the internal side of said body near one edge, and a rubber member disposed in said container and connected at one end to said fixture near one edge thereof and at the other end to the container in spaced relation to said hole for yieldably holding said closure in closed position.

2. In a container having two side and two end walls and top and bottom: means defining an opening in the upper portion of one of the end walls, a panel mounted on the inner side of said portion and having a hole therein smaller than said opening and in conjunction with said portion forming a recess around said hole, a closure having an inwardly protruding body with a recess on its external side, a radially extending flange joined integrally to and disposed around the edge of said body for seating in said first mentioned recess around said hole, and a resilient means disposed in said container and connected at one end to said body near one edge thereof and at the other end to the container in spaced relation to said hole for yieldably holding said closure in closed position.

3. In a container having two side and two end walls and top and bottom: means defining an opening in the upper portion of one of the end walls, a panel mounted on the inner side of said portion and having a hole therein smaller than said opening and in conjunction with said portion forming a recess around said hole, a closure having an inwardly protruding body with a recess on its external side, a radially extending flange joined integrally to and disposed around the edge of said body for seating in said first mentioned recess around said hole, a rubber member disposed in said container and connected at one end to said body near one edge thereof and at the other end to the container in spaced relation to said hole for yieldably holding said closure in closed position.

4. In a container having two side and two end walls and top and bottom: means defining an opening in the upper portion of one of the end walls, a panel mounted on the inner side of said portion and having a hole therein smaller than said opening and in conjunction with said portion forming a recess around said hole, a closure having an inwardly protruding body with a recess on its external side, a radially extending flange joined integrally to and disposed around the edge of said body for seating in said first mentioned recess around said hole, a rubber member disposed in said container and connected at one end to said body near one edge thereof and at the other end to the container in spaced relation to said hole for yieldably holding said closure in closed position, and a flap attached to said container above said recess for overlapping said closure for releasably holding said closure in closed position.

5. In a container having two side and two end walls and top and bottom: means defining a round opening in the upper portion of one of the end walls, a panel mounted on the inner side of said portion and having a round hole therein smaller than said opening and in conjunction with said portion forming a recess around said hole, a closure having a dome-shaped body with a hemispherical recess on its external side, a handle extending across said body recess and a laterally extending annular flange joined integrally to and disposed around the external edge for seating on said panel in said first mentioned recess and around said hole, a fixture secured to the internal side of said body near one edge, a resilient means disposed in said container and connected at one end to said fixture near one edge thereof and at the other end to the container in spaced relation to said hole for yieldably holding said closure in closed position, and a flap attached to said container above said recess for overlapping said closure.

6. In a container having two side and two end walls and top and bottom: means defining a round opening in

the upper portion of one of the end walls, a panel mounted on the inner side of said portion and having a round hole therein smaller than said opening and in conjunction with said portion forming a recess around said hole, a closure of plastic material having an inwardly protruding, dome-shaped body with a hemispherical recess on its external side, a handle extending across said body recess and a laterally extending annular flange joined integrally to and disposed around the external edge for seating on said panel in said first mentioned recess and around said hole, a fixture secured to the internal side of said body near one edge, a rubber member disposed in said container and connected at one end to said fixture near one

edge thereof and at the other end to the one side wall of said container for yieldably holding said closure in closed position, and a flap attached to said container above said recess for overlapping said closure and for releasably holding said closure in closed position.
